UNITED STATES PATENT OFFICE.

GEORGE DUNHAM, OF UNIONVILLE, CONNECTICUT.

METAL-SHAVING MACHINE.

1,124,876.

Specification of Letters Patent. Patented Jan. 12, 1915.

Application filed April 18, 1914. Serial No. 832,743.

To all whom it may concern:

Be it known that I, GEORGE DUNHAM, a citizen of the United States, residing at Unionville, in the county of Hartford and 5 State of Connecticut, have invented a new and Improved Metal-Shaving Machine, of which the following is a specification.

My invention relates more especially to the class of metal shaving machines that are 10 employed for shaving nuts and like articles, and an object of my invention, among others, is to provide a machine of this class, that shall be simple in construction and particularly efficient in operation.

15 One form of machine embodying my invention, and in the construction and use of which the objects herein set out, as well as others, may be attained, is illustrated in the accompanying drawings, in which—

20 Figure 1 is a top plan view of a device embodying my invention, with parts removed to show construction. Fig. 2 is a view in vertical section through the same on plane denoted by dotted line 2—2 of Fig. 1.

25 Fig. 3 is a view in vertical section through the device on plane denoted by dotted line 3—3 of Fig. 1. Fig. 4 is a fragmentary view in cross section through the shaving tools.

30 My invention relates particularly to the machine forming the subject matter of my co-pending application of Serial Number 670,200, filed January 9th, 1912, one object of the present invention being to particularly increase the efficiency of the machine 35 shown in the prior application.

35 In the accompanying drawings the numeral 6 denotes a block or cutter holder, of any suitable form and material, with a recess 7 extending downwardly from the top 40 for a short distance. In the preferred form of construction, and as shown herein, the block includes a sleeve 8 closely fitting its main part, which is preferably round, said sleeve extending above this main part a distance sufficient to provide the recess of the 45 required depth. The base 9 of the block may be provided with holes or other suitable means for securing it to a bench or other structure. A well 10 extends from the bottom 50 of the recess downwardly into the block, for a suitable distance, and a central opening 11 and relief openings 12 extend from the bottom of the well through the block to the bottom thereof, the surface between the openings 12 constituting rests for finishing cutter 55 blades 13 located in cutter slots 14 formed in

the block in the direction of depth and radially thereof, and extending from the outer edge of the main part of the block into the well. The ends of the blades 13 projecting 60 into the well 10 comprise cutting surfaces, the side of each blade being beveled as at 15, which beveled part extends from the top at one side downwardly to the opposite side, terminating preferably at a distance from 65 the bottom of the blade. This beveled side forms a cutting edge 16 at the end, which edge is diagonally disposed to the direction of movement of a nut, which movement is in a direction axially of the well 10. The ridge 70 or apex 17 of this cutting edge is located at one side of the blade so that it will not come in contact with the nut in the cutting operation, said nut first encountering the beveled edge that exerts a shearing cut as the nut is 75 forced downward. Each of the blades is cut away as at 18, within which cut-away portion the lower part of the end of an adjacent blade is located, as shown in Fig. 3 of the drawing.

80 A spacer 19 rests upon the beveled surface of each blade with a retaining lip 20 on each spacer resting upon the apex of a blade and the adjoining bottom surface of the recess 7. The inner ends of these spacers are located 85 at some distance back from the cutting edges of the blades 13 and the lower edges of the spacers are spaced from the side surfaces of the cutter slots 14.

85 Roughing cutters 21, resting upon the 90 spacers 19, each have two beveled sides 22—23 terminating in ridges or apexes 24 preferably located in the path of movement of the nut as it is forced downwardly in the cutting operation. The longer beveled sides 95 22 terminate at vertical sides 25, which vertical sides rest against the sides of the cutter slots 14. Clamps 26 extend over the apexes 24, the bases 27 of the clamps being secured, as by means of bolts, to the bottom 100 surfaces of the recess 7, the front edges of the clamps being set back from the cutting edges of the cutter blades. The roughing cutters 21 are, in fact, sizers, that is, they cut all of the nuts to preferably uniform 105 size before they are presented to the finishing cutting blades 13, and these roughing cutters also have the function of gages or guides to direct the movement of a nut in its downward course, and to hold it steadily 110 during the cutting operation. The openings 12 serve as clearance openings to relieve

the well of chips and other dirt that would otherwise obstruct the cutting operation. The cutter blades are backed up by adjusting screws 28 that serve as a means for adjusting the position of the cutters relatively each to the other.

While I have shown and described herein a satisfactory construction of my improved device, it will be understood that this may 10 be departed from to a greater or lesser degree and yet be within the spirit and intent of the invention.

In many instances the amount of metal taken from the nut by the finishing cutting 15 blades will be very slight, the ends of the finishing cutting blades being set a slight distance nearer the center of the holder than are the cutting ends of the sizers, and this may be so slight as not to be perceptible in 20 the drawings although it will be understood that the drawings do show the ends of the finishing cutting blades slightly in advance of those of the sizers.

I claim—

25 1. A holder, cutter blades angularly disposed in said holder and converging toward a common center, the ends of the blades constituting the cutting portion that are beveled laterally and that are disposed for the 30 passage of an article to be shaved, sizers supported by the beveled sides of said cutter blades and with their cutting ends arranged slightly back of the cutting ends of the cutter blades, and means for holding the 35 sizers in place.

40 2. A holder, cutter blades angularly disposed in said holder and converging toward a common center, the sides of the blades being beveled laterally to provide a shearing cutting edge at the end of each cutting blade, spacers supported upon the beveled sides of the blades, sizers supported upon said spacers with their cutting ends slightly back of the 45 cutting ends of the blades, and means for holding the sizers in place.

45 3. A holder, cutter blades angularly disposed in said holder and converging toward a common center, the sides of the blades be-

ing beveled to form a shearing cutting end with an apex located at one side of the blade, 50 sizers supported by said blades and having beveled sides forming an apex located in a vertical line between the edges of the cutter blades, and means for holding the sizers in place.

55 4. A holder having radial grooves, cutter blades disposed in said grooves and having sides beveled laterally of the blade, said sides extending below the upper edge of the grooves, sizers supported above the cutter blades within said grooves, said sizers having straight sides resting against the sides of the grooves and also beveled sides constituting cutting ends with shearing edges, and means for holding the sizers in place.

60 5. A holder having radial grooves, cutter blades located within said grooves and having beveled portions extending from one side to the opposite side of each blade forming a cutting end with a shearing edge on 70 each blade, and the beveled part of each blade being located below the upper edges of said grooves, sizers supported above the cutter blades and having straight sides resting against the sides of said grooves and 75 with a beveled upper edge providing a point located in a vertical line between the sides of the cutter blades, and means for holding the sizers in place.

65 6. A holder having radial grooves, cutter 80 blades located in said grooves and having the sides beveled laterally forming a cutting end having a shearing edge, spacers located above the beveled surface of said blades, sizers resting upon said spacers and having 85 beveled sides providing ends with shearing edges, and clamps having lips overlying the points on the sizers, the bases of the clamps being secured against the horizontal surface of the holder to clamp the blades and 90 sizers in place.

GEORGE DUNHAM.
